UNITED STATES PATENT OFFICE.

JAMES EDWARD LAWRENCE, OF WEST SHEFFORD, CANADA, ASSIGNOR OF ONE-HALF TO VICTOR MARCHESSAULT, OF WEST SHEFFORD, CANADA.

TEMPERING-BATH.

SPECIFICATION forming part of Letters Patent No. 706,966, dated August 12, 1902.

Application filed June 29, 1901. Serial No. 66,509. (No model.)

To all whom it may concern:

Be it known that I, JAMES EDWARD LAWRENCE, a subject of the King of England, and a resident of West Shefford, in the Province 5 of Quebec and Dominion of Canada, have invented new and useful Improvements in Hardening-Baths, of which the following is a full, clear, and exact description.

The object of the invention is to provide a 10 new and improved bath designed for hardening steel or other metallic articles, especially such as dies, tools, and the like, and which require a hard face and a softer back.

The invention consists, essentially, of superimposed liquids, of which one is capable 15 of floatingly supporting the article to be hardened.

Reference is to be had to the accompanying drawing, forming a part of this specification, 20 in which the figure is a sectional side elevation of the improvement.

As shown in the drawing, the superimposed liquids A and B, preferably mercury and oil, are contained in the vessel C, set in another 25 vessel D, containing a cooling liquid E. The heated article F to be hardened is placed downward into the bath, as shown, and since the specific gravity of the mercury is greater than that of the article the article will float 30 upon the mercury, sinking only a short distance into the mercury, so that the face portion of the article is subjected to the action of the mercury and the upper or back portion is submerged in the oil and is hence subjected to the action thereof. The article is 35 left immersed in the bath until it is cool. The action of the mercury on the article F causes the face thereof to be hardened to a very high degree, while the oil leaves the back of the 40 article less hard.

It is evident from the foregoing that a fixed degree of hardness is given to one portion of the article and a different degree of hardness is given to the remaining portion without requiring any attention on the part of the operator. Thus by allowing the article to float it is automatically hardened to the desired degree.

By the use of suitable tools or other devices the article F may be forced downward farther into the mercury E, or it may be completely immersed, if desired, or the article may be first forced quickly through the oil into the mercury to quickly and mainly cool the same and then withdraw into the oil to slowly 55 finish cooling it.

By employing a bath formed of two liquids one of which is of greater specific gravity than the article to be hardened the article is rendered self-adjusting as to its position relative to the hardening liquids employed, thereby facilitating the operation and also producing a more even hardness of the surfaces of the article. By forming the bath of oil and mercury the two liquids, owing to the great 65 difference in specific gravity, are not liable to mix or freeze in ordinary cold weather.

Having thus described my invention, I claim as new and desire to secure by Letters Patent—

1. A hardening-bath, comprising a metallic liquid, and a superimposed liquid of less specific gravity than the metallic liquid, as set forth.

2. A hardening-bath, comprising a metallic 75 liquid and oil superimposed thereon, as set forth.

3. A hardening-bath, comprising mercury, and a superimposed liquid of less specific gravity than the mercury, as set forth.

4. The herein-described hardening-bath, 80 consisting of oil superimposed on mercury, as set forth.

5. The herein-described hardening-bath, comprising a vessel containing oil, superimposed on mercury, and a second vessel in which the first-named vessel is set, the second vessel containing a cooling liquid, as set forth.

In testimony whereof I have signed my 90 name to this specification in the presence of two subscribing witnesses.

JAMES EDWARD LAWRENCE.
